UNITED STATES PATENT OFFICE.

ALEXANDER ADAMSON, OF AKRON, OHIO.

VULCANIZER.

1,368,679.

Specification of Letters Patent. Patented Feb. 15, 1921.

Application filed December 2, 1920. Serial No. 427,871.

To all whom it may concern:

Be it known that I, ALEXANDER ADAMSON, a citizen of the United States, residing at Akron, in the county of Summit and State 5 of Ohio, have invented new and useful Improvements in Vulcanizers, of which the following is a specification.

This invention relates to vulcanizers and has particular reference to a new and useful 10 improvement in closure devices which may be employed to advantage on vulcanizers and as well on other open mouthed receptacles.

It is an object of the invention to provide 15 a strong, durable vulcanizer, of simple, economical construction, and to provide an easily operated, highly efficient closure device therefor.

An important object is to provide an extremely 20 simple, durable mechanism whereby a suitable cover may be hinged to a receptacle so that the cover when opened and closed will swing in a comparatively small space and to thereby provide means whereby 25 a greater number of vulcanizers may be positioned in a given area.

A further object is to provide a means for operatively supporting said closure member which will be easily and quickly 30 adjustable to compensate for the wear incident to constant use.

The above and additional ends are attained by the novel construction, combination and arrangement of parts hereinafter 35 described and illustrated in the accompanying drawings which form a part hereof and wherein I have shown a preferred embodiment of the invention, it being understood that the invention is capable of various 40 adaptations and that changes, variations and modifications may be made or substitutions resorted to which come within the scope of the claims hereunto appended.

In the accompanying drawings in which 45 similar characters of reference are employed to designate like and corresponding parts throughout the several views and in which:—

Figure 1 is a perspective view of a vulcanizer showing the mouth thereof closed by a device constructed in accordance with this invention.

Fig. 2 is a perspective view showing said closure device swung back in an opened position.

Fig. 3 is a central, vertical, sectional view

of the cover portion of a vulcanizer showing my improved closure device in a closed position.

Referring now to the drawings in detail, the reference numeral 5 denotes the body of the vulcanizer which is preferably constructed in the form of a hollow horizontal cylinder, provided with one opened end 6. The numeral 7 is used to denote an annular collar which is secured to the opened end 6 of the vulcanizer body 5, by means of the rivets 8 or other suitable fastening means, so as to project therebeyond. The outwardly projecting portion of the collar 7 is 65 fashioned to provide a circumferentially extending bell flange 9, the inner face of which is provided with a bearing face 10 which extends therearound and is disposed at a right angle to the axis of the vulcanizer so as to 70 form a seat for the closure member to be hereinafter described. The bearing face 10 is provided with an annular channel 11 adapted to receive a suitable packing ring 12. The bell flange 9 is provided adjacent 75 its outer edge with a plurality of spaced, internal, regularly recurring lugs 13 which project inwardly and radially therefrom, thus providing a notch 14 between each lug 13. The lugs 13 and the notch 14 are of 80 approximately the same circumferential width and are alternately disposed around the entire inner face of the bell flange 9. The closure device comprises a circular head 85 90 which is provided on its inner side adjacent its peripheral edge with an annular bearing face 16 which is adapted to coincide with the bearing face 10 on the collar 7 when the head 15 is in a closed position. The head 15 is provided on its peripheral edge with a plurality of spaced radial outwardly projecting lugs 17, thus providing 95 the notches 18. The lugs 17 on said closure device correspond in circumferential width with the notch 14 on the flange 9; and, likewise, the notch 18 on the closure device and the lugs 13 on the flange 9 are of approximately the same circumferential width so that the closure member may be forced inwardly against the bearing face 16 when 100 placed in coaxial alinement with the vulcanizer 5 and with the lugs 17 in alinement with the notch 14.

The vulcanizer head 15 is constructed with an outwardly projecting annular bulge 110 19 which is formed therein in spaced relation to the periphery thereof. The center

portion of said head is bulged inwardly to provide a cylindrical protuberance 20 which projects inwardly and coaxially therefrom, thus providing a cylindrical bore 21 which 5 extends into the outside of said head and constitutes a housing for the universal joint to be hereafter described. The said bore 21 is provided with screw threads 22 which are adapted to receive the external threaded, 10 socketed, bearing block 23. The numeral 24 is used to denote a bolt-like member which is provided with a ball head 25 adapted to seat in the socket 26 in said block 23 so that the said ball 25 may be retained in said bore 15 21 by means of said block 23 with the shank of the member 24 projecting outwardly through said socket 26. The numeral 27 denotes a coil spring which is compressed between the ball head 25 and the inner wall 20 28 of said bore 23 so as to maintain the ball head 25 in a seated position in said socket 26. It will be seen that with the member 25 secured in a horizontal position as herein-after described, the head will be secured 25 thereto so as to allow a limited movement of said vulcanizer head 15 in every direction. The collar 7 is provided on one side thereof with a pair of integral lugs 29 and 30 which project outwardly therefrom in 30 spaced parallel relation, each lug is provided with a vertical bore which is formed therein with the said bores in alinement with each other and a suitable pin 31 is mounted in the said vertical bores so as to be rotatable on a vertical axis. An arched arm 32 is rigidly secured to the upper end of the pin 31 so as to extend upwardly and radially therefrom. The arm 32 is thus hinged to the collar 7 so that it may be 40 swung in a horizontal plane and is constructed of sufficient length so that the free end thereof may be directly above the center of the vulcanizer head 15 when the same is operatively secured in the mouth of the 45 said vulcanizer. The free end of the arm 32 is provided with a tapered bore 33, which is relatively small at the upper end and which is countersunk to provide a seat 35 for the bearing block 34. The lower surface of the 50 block 34 conforms in contour to a portion of the surface of a sphere and the seat 35 is constructed to receive said spherical surface. The bearing block 34 is provided with a vertical bore which extends through the center 55 thereof. The numeral 36 denotes a bolt-like member which extends upwardly through the tapered bore 33 and through the bore in the block 34 so as to project upwardly therebeyond. The upper end of said 60 bolt-like member is provided with screw threads and the member is secured in said block 34 by means of the nuts 37 or other suitable fastening means. The lower end of the bolt-like member 36 is rigidly secured 65 to a vertical arm 38 which extends out-

wardly and downwardly therefrom and terminates at a point approximately central of the vulcanizing head 15 when the same is secured in the mouth of said vulcanizer. The lower end of said arm 38 is provided with a horizontal bore which is adapted to receive the bolt-like member 24 hereinbefore described. The outwardly extending end of said bolt-like member 24 is threaded and the same is secured in a horizontal position 70 therein by means of the nuts 39 or other suitable fastening means. It will thus be seen that the upper end of the vertical arm 38 is secured to the upper end of the arm 32 by means of a universal joint which will permit a limited movement of the lower end of said arm in every direction. The inner face 40 of said vertical arm 38 is flat and is provided with a lug 41 which projects inwardly from said face. The lug 41 is provided 75 with a suitable bore 42 which extends laterally therethrough. The head 15 is likewise provided with integral lugs 43 and 44 which project outwardly therefrom in spaced relation to each other and at points adjacent the outer circumferential edge of the head 15. Each of the lugs 43 and 44 is provided with a bore in which the guide rod 45 is rigidly mounted so as to extend from one lug 43 to the other 44. The rod 45 also extends 80 through the bore 42 in the lug 41 which is positioned between the other two lugs 43 and 44. The bore 42 is substantially larger than the rod 45 and the vulcanizer head 15 is thus additionally secured to said vertical 85 arm 38 with the lug 43 on one side of the vertical arm 38 and the lug 44 on the other side thereof thus limiting the movement of the head on the ball 25. The numeral 47 is used to denote suitable lugs which project 90 outwardly from the outer surface of the vulcanizer head 15 and the numeral 46 denotes a handle which is mounted in suitable bores in said lugs 47 so as to project outwardly beyond the peripheral edge of the vulcanizer 95 head 15 and beyond the flange 9 when the head 15 is secured in the mouth of said vulcanizer.

It will be noted that the bearing block 23 may be positioned in the threaded bore 21 115 at any desired depth and that the center of gravity may thus be shifted as desired. It will also be seen that the peculiar construction of the cylindrical head 15 permits the same to be hung on said ball 25 so as to be 120 balanced thereon and the same may be easily maintained on a horizontal axis.

In operation the head 15 is carried close to the mouth 6 of the vulcanizer by swinging the same on the arm 32. The head is then 125 given a rotary movement to bring the lugs 17 on said head in alinement with the notches 14 on the flange 9. The head is then moved inwardly until its face 16 is in contact with the face 12 on said collar 7. The lugs 130

are thus forced inwardly past the lug 13 on said flange 9 and force is then applied to the handle 46 and the head 15 is given a rotary movement which moves the lugs 17 back of 5 the lugs 13, thus securing the head 15 in the mouth of said vulcanizer.

In opening a vulcanizer constructed in accordance with this invention, force is applied to the handle 46 and the lugs 17 are 10 brought into alinement with the notches 14 and the head 15 is brought outwardly in a straight line until it has cleared the flange 9 and is out of contact with the lugs 13, whereupon the vertical arm 38 is gradually 15 turned while the arm 32 is swung to the position shown in Fig. 3. A careful examination of the drawings, and particularly Fig. 3, discloses an important advantage of the invention, inasmuch as it will be noted that 20 the head 15 can be swung to an open position in a relatively small space, and if desired the same may be folded back flat against the side of the body 5.

It will also be noted that the various 25 parts are so constructed and assembled as to be quickly and easily adjusted should adjustment be necessary, because of wear or for any other reason, and that the herein described device may be so adjusted while 30 in use.

Having thus described my invention what I claim as new and desire to secure by Letters-Patent is:—

1. A vulcanizer comprising a horizontal 35 receptacle having an open end, a collar secured around said open end, an arm hinged on said collar so as to swing on a vertical axis; said arm extending upwardly and outwardly so that its free end may be swung 40 above the said collar, a vertical member secured to the free end of said arm by means of a universal joint so as to depend downwardly therefrom; a vulcanizer head adapted to be received in interlocking engagement by said collar, said head secured to 45 the lower end of said member by means of a universal joint and means to limit the movement of the head relative to said member.

50 2. A vulcanizer comprising a horizontal receptacle having an open end, an arm hinged on said receptacle so as to be rotatable on a vertical axis, a vertical supporting member secured to the free end of said arm so as to be rotatable on a vertical axis, a horizontal rod fixed to the lower end of said member, a vulcanizer head fixed to said rod so as to be rotatable on a horizontal axis

and means to additionally secure said head to said supporting member and limiting the 60 movement thereof on said rod.

3. A vulcanizer comprising a horizontal receptacle having an open end, a collar secured around said open end, a head for said receptacle, said head and said collar provided with interlocking portions so that the head may be secured therein; an arm hinged on said collar so as to be rotatable on a vertical axis, a vertical supporting member adjustably secured to the free end of said arm 70 so as to be rotatable on a vertical axis and so the free end thereof may be given a limited lateral movement in any direction, the lower end of said member connected to the central portion of said head by means 75 of a ball and socket joint and means to limit the movement of said head relative to said member.

4. In a vulcanizer, a suitable receptacle having an opening, a collar on said opening, 80 a cover adapted to fit into said collar, means to hinge said cover on said collar so that the same may be given a swinging movement on a vertical axis and rotated on a vertical axis and means to lock said cover in said collar. 85

5. In a vulcanizer, a suitable receptacle having an opening, a collar on said opening, a cover adapted to fit into said collar, said cover supported by an arm hinged on said collar so as to be swung in a horizontal 90 plane, the said cover hinged to said arm so as to be rotatable on a vertical axis and given a limited rotary movement in a horizontal axis, said cover and said collar provided with interlocking portions whereby 95 the former may be secured in the latter by giving the same a limited rotary movement.

6. In a device of the class described, a suitable receptacle having an opening; a collar on said opening; a cover adapted to 100 fit into said collar, interlocking means whereby the cover may be secured in said collar; an arm hinged to said collar so as to swing in a horizontal plane; a cover-supporting member hinged to said arm so as to depend 105 therefrom and be rotatable on a vertical axis and so the lower end thereof may be given a limited lateral swinging movement in every direction, the lower end of said member being hinged to said cover so that the latter may be given a limited universal movement on a normally horizontal axis substantially as herein set forth.

In testimony whereof I have hereunto set my hand.

ALEXANDER ADAMSON.
